UNITED STATES PATENT OFFICE.

HARRY BARNOWITZ, OF BROOKLYN, NEW YORK.

CLASP.

Application filed September 10, 1924. Serial No. 736,996.

To all whom it may concern:

Be it known that I, HARRY BARNOWITZ, a citizen of the United States, and a resident of the city of New York, borough of Brooklyn, in the county of Kings and State of New York, have invented a new and Improved Clasp, of which the following is a full, clear, and exact description.

This invention relates to clasps and more particularly to a clasp designed for use in connection with garters, belts or other similar articles, an object of the invention being to provide a clasp in which it is practically impossible for the members to be accidentally disconnected, but which permits of ready connection and disconnection by proper manual manipulation.

A further object is to provide a clasp which may be so mounted with relation to the garter or other article that the metal of the clasp is held out of contact with the flesh, the stocking or other garment.

A further object is to provide a clasp of this character which can be manufactured and sold at a reasonably low price, which will be neat and attractive in appearance and which will most efficiently perform the functions for which it is intended.

With these and other objects in view, the invention consists in certain novel features of construction and combinations and arrangements of parts which will be more fully hereinafter described and pointed out in the claim.

In the accompanying drawings—

Figure 1 is a view in elevation illustrating the two members of my improved clasp disconnected from each other but connected to different portions of the garter or belt;

Figure 2 is a view in longitudinal section showing the clasp members in coupled position;

Figure 3 is a view similar to Figure 2, showing the position the clasp members will assume on accidental contraction of the garter or belt, as the case may be.

My improved clasp comprises a socket member 1 and a hook member 2. The socket member 1 is preferably formed from a single plate having slots 3 and 4 adjacent its side edges for the reception of the garter material or belt material 5, which may be laced through the slots 3 and 4, and secured

in any approved manner so that, at least, a portion of the material 5 is positioned back of the plate 1 to prevent contact with the stocking or flesh.

This plate 1 is preferably cut out as shown at 6 for lightness and also for ornamentation. The center of the plate 1 is laterally offset as shown at 7. This offset portion is circular in form and is made with a circular opening 8 to receive a hook 9 on the other clasp member 2. This hook 9 is made integral with a loop 10 and through this loop the other end of the garter or belt material is projected and secured in any approved manner. It will be noted that the hook 9 is of a width just slightly less than the diameter of the opening 8 and that the tongue or return bend portion 11 of the hook is of a length sufficient to allow it to pass freely through the opening 8.

Figure 2 shows the normal position of the clasp members when in locked engagement. If the garter or belt should be accidentally contracted, the free end of the hook 9 will ride into or under the offset portion 8 and remain coupled to the plate member 1. As soon as the garter or belt is again expanded, the parts will return to the position shown in Figure 2.

To release one member from the other, the hook must be moved forward and then at a right angle, or a tilting action imparted thereto, to disengage the hook from the plate 1. In other words, this laterally offset portion 7 performs a very important function. Not only does it house the inner end of the hook but it provides ample space for the hook to accommodate itself thereunder in the event of accidental movement or ordinary movement which might be imparted to the clasp and which would tend to release the hook, if the plate were flat.

The offset portion 7 with its opening 8 constitutes in effect an annular socket providing accommodation or housing for the end of the hook, requiring a manual manipulation of the hook relative to the clasp to accomplish a release of the parts.

Various slight changes and alterations might be made in the general form of the parts described without departing from my invention, and hence I do not limit myself to the precise details set forth but consider

myself at liberty to make such slight changes and alterations as fairly fall within the spirit and scope of the appended claim.

I claim:

5 A clasp, comprising a socket member and a hook member, the socket member comprising a plate having a laterally offset portion forming a circular chamber, the outer wall of said chamber having a central opening therein of appreciably less diameter than the diameter of the chamber, said opening adapted to receive the hook

and permit engagement of the hook with the wall of the opening, said chamber being of sufficient diameter and depth to accommodate as an entirety the bent portion of the hook under the wall thereof when a longitudinal movement is imparted to the hook with the latter at an angle to the plane of the socket member, whereby the chamber will receive and accommodate the hook and prevent accidental uncoupling. 15 20

HARRY BARNOWITZ.
